UNITED STATES PATENT OFFICE.

MAX OTTO CLAUSS, OF NEW YORK, N. Y., ASSIGNOR TO THE CLARK THREAD COMPANY, OF NEWARK, NEW JERSEY, A CORPORATION OF NEW JERSEY.

SKEIN.

1,401,521.

Specification of Letters Patent. Patented Dec. 27, 1921.

Application filed July 10, 1920. Serial No. 395,309.

To all whom it may concern:

Be it known that I, MAX OTTO CLAUSS, a citizen of the United States, and resident of the borough of the Bronx, in the county of Bronx and the city and State of New York, have invented certain new and useful Improvements in Skeins, of which the following is a description.

The invention relates to an improvement 10 in skeins.

Skeins of yarn, cotton, silk and the like for embroidery, knitting, crocheting and other purposes are put on the market in such form that they must be untwisted or unfolded before a strand or loop of thread can be removed without entangling the other threads or loops. Many efforts have been made to obviate the necessity of untwisting or unfolding the skeins before a 20 small portion thereof can be used, and to this end, it has been proposed to inclose the skeins in packages so constructed that when the ends of the loops are cut the individual strands or single loops may be drawn out one at a time without entangling the other threads. These packages are more or less expensive to manufacture, and inclosing the skeins in this manner necessitates the withdrawal of a complete loop at one time, 30 whether or not only a portion of a loop is desired. It has also been proposed to put skeins on the market in other forms in order to obviate the entangling of the threads either in the skein itself or with the threads 35 of other skeins contained in the receptacle or work basket of the user. None of these efforts have been successful as a commercial proposition because, so far as known, the usual and commercial form of skein consists of a number of loops so interfolded that the skein cannot be unwound unless the bands are removed from the skein and the skein untwisted or unfolded.

The object of the invention is to produce 45 a skein formed in such manner that the skein may be put on the market and used in the condition in which it comes from the winding machine, and which may also be opened out or unfolded into a series of simple loops, as is the practice with skeins wound according to the usual practice now obtaining. The skein of the present invention is so constructed that while it is in its 55 relatively short market length, held together with the usual band or bands, it is in

such condition that any desired length or strand may be drawn therefrom without entangling the remaining strands or loops. The skein is so wound that when it comes from the skein winding machine it is of this 60 relatively short length. Not only may the skein be used in the condition in which it comes from the skein winding machine, but it also may be opened up or unfolded into a skein of the usual length.

The improved skein comprises a series of main or primary loops, having associated with them a plurality of series of intermediate or subsidiary loops. These main or primary loops and intermediate or subsidiary loops are so associated that the skein composed of them may be unwound by pulling on or drawing out the proper strand, or the intermediate or subsidiary loops may be separated from the main or primary loops 70 to form the skein into a series of simple loops. The improved skein may be wound in a number of ways and in the accompanying drawing I have illustrated some of the ways in which the skein may be formed. 80 The invention itself is described in the following specification and particularly pointed out in the appended claims.

Figure 1 is a diagrammatic view illustrating the fundamental principle involved in 85 the winding of the skein.

Fig. 2 is a similar view, illustrating a second phase in the development of the skein.

Fig. 3 is a diagrammatic view showing 90 one complete cycle of the winding operation in the preferred embodiment of the invention.

Fig. 4 is a plan view illustrating the completed marketable product, and,

Fig. 5 is a diagrammatic view showing a slightly modified method of winding the skein.

The improved skein of the present invention as illustrated in Fig. 4 and wound according to the methods diagrammatically shown in Figs. 2, 3 or 5, consists of a continuous strand or thread formed into a skein of comparatively short length, from which the thread may be withdrawn without entanglement of the looped thread strands. I have found in practice that this can best be accomplished by winding the thread in the general form of a triangle as shown at 5, in Fig. 1 of the drawings, the thread being car- 110

ried around spaced points 6 at one end of the skein, and a single point 7 at the opposite end of the skein. However, if the thread were carried directly around these spaced points 5 in succession from one point to the other, the skein would be in such condition that it could not be opened out or unfolded into a skein of the regular length, if that were desired and, therefore, I propose to form in 10 the thread and within the circuit of the main or primary loop a plurality of secondary or subsidiary series of looped strands, as shown at 8, Fig. 2, before closing the main or primary skein loop by completing the cycle 15 of the winding evolution.

In order that the several looped strands of the skein shall not become entangled with each other when the thread is withdrawn, and the loops straightened out, it is essential 20 that in the winding evolution the looped strands shall not cross or intersect each other. Accordingly, the thread is wound in the manner illustrated in Fig. 2, and starting from one of the horizontally spaced 25 points 6, the thread is first carried to the other point 7, as at *a*, defining the opposite end of the skein, and is then returned upon itself, as at *b*, without intersecting the strand *a*, and carried around the starting point 6, 30 and then again returned, as at *c*, to the opposite end of the skein and carried around the point 7, and then carried to the other of the horizontally spaced points 6, as at *d*. From this latter point the thread is re- 35 turned upon itself to form the second subsidiary loop, as at *e*, and around the point 7, with which the other looped strands have common engagement. The thread is finally again reversed, as at *f*, and extended around 40 and across the horizontally spaced points 6 to the starting point. This completes a single winding evolution, and is repeated until the desired length of thread has been wound upon the spaced points. In this manner 45 it will be seen that there is produced a relatively short skein, which is made up first of the multiplicity of strands *a* and *f*, extending along either side of the triangular skein figure, and across the wider end 50 thereof, which constitute the primary main or skein loops, and within the circuit of which the plurality of series of intermediate or subsidiary loops, each consisting of a multiplicity of looped strands *e*, *c* and *d*, *e* 55 respectively, are formed.

After the thread length has thus been wound, a suitable binder, indicated at 9, is applied to the portion of the primary looped strands *a*, *f*, which extend between the horizontally spaced points above referred to, and a tubular label, indicated at 10, is then longitudinally slipped over the opposite ends of the primary and subsidiary skein loops to draw the same together into more 65 or less compact relation, as indicated in Fig.

4. The ends of the skein thread, shown at 11, are left projecting in opposite directions from the wide end of the skein to which the binder 9 is applied. In withdrawing the thread from the skein, the end of the thread 7 at which the winding evolutions were started is grasped and pulled. The individual looped strands of the series of skein loops making up the completed skein will then readily separate from all of the remaining 7 looped strands of the skein without becoming entangled with the latter. This, it will be seen, is due to the fact that these strands do not intersect with each other, so that as the strand is withdrawn, there will be no 8 cross or positive pulling contact with the adjacent strand, as would be the case if the direction of pull was across or at an angle to the adjacent looped strand.

In Fig. 5 of the drawings I have illustrated another manner of winding the thread or filament, wherein the skein is wound around the four spaced points or supports designated 12, 13, 14 and 15 respectively, the points 12 and 14, and 13 and 15 being arranged in laterally spaced relation to each other, and defining the opposite ends of the skein length. The thread or filament is first engaged around the point 12, and then carried to the point 13, and 91 reversed, and extended again around the point 12, and returned to the point 13 to form an intermediate or subsidiary loop *g*. The thread is then carried laterally to the point 15, then longitudinally around the 10 point 14, and returned to the point 15 to form a second intermediate or subsidiary loop, as at *h*. The thread or filament is now carried again around the point 14, and extended to the point 12 to close the main 11 or primary loop, the latter loop being designated by the letter *i*. Thus in this case it will be seen that in each winding evolution in addition to the main or primary looped strand of the thread or filament, two 11 subsidiary looped strands are formed in parallel relation with each other, and no one of these looped strands intersects with any of the other looped strands. This operation is repeated until the desired length of the 11 thread or filament has been wound to complete the skein. The series of skein loops, each consisting of a multiplicity of looped strands, are then removed from the supporting points, and the two series of subsidiary loops *g* and *h* are brought together in more or less compact relation, and the tubular label 10 then engaged over the skein in the manner above described, after which the binder is applied to the end of the primary skein loops *i*, from the opposite sides of which the extremities of the thread or filament extend. Therefore, it will be apparent that a skein wound in this manner also possesses the several advantages here- 11

inbefore referred to, and by pulling upon the end of the proper thread, the thread may be readily withdrawn from the skein without liability of entangling the looped strands thereof.

It will be recognized from the above description that the improved skein, in addition to being unwindable without entanglement simply by pulling on or drawing out the proper thread, is unfoldable into a skein of greater length than the original skein by separating the intermediate or subsidiary loops from the main or primary loops. Whether the skein will be used in the form shown in Fig. 4, in which condition it comes from the skein winding machine, or whether the skein will be unfolded by separating the intermediate from the main loops, will depend upon the conditions under which the skein is used. For private or household use the skein will preferably be used in its original form, as shown in Fig. 4, and for general manufacturing purposes it will be opened out into a series of simple loops and the ends cut to constitute a series of strands of uniform length.

From the foregoing description, considered in connection with the accompanying drawings, the construction and several advantages of my invention will be readily understood. The loss of time and the manual exertion incident to the necessity of first winding the thread or filament into a ball in the use of skeins in crocheting as has been the practice heretofore is eliminated by means of the present invention. This skein is also advantageous in embroidery work, since any desired length of the thread or filament may be withdrawn from the skein without disassociating the series of looped strands, or entangling the same with each other, and such withdrawn length of the thread or filament cut off.

The embodiments of the invention herein disclosed, and particularly that illustrated in Figs. 1 to 4 inclusive of the drawings, contemplate the winding of one hundred yard skeins to produce a completed skein, which will be of relatively short length, without being unduly bulky. It is, however, manifest that if desired a greater or less length of the thread or filament may be comprised in each skein. It will, therefore, be understood that the present invention is not to be limited to the specific examples of the skein windings, herein referred to, but

the essential feature thereof may likewise be incorporated in numerous other alternative constructions, and I accordingly reserve the privilege of adopting all such changes and modifications as may be fairly embodied within the spirit and scope of the invention as claimed.

Having thus described the invention what I claim as new is;

1. A skein composed of a continuous length of thread formed into a series of main or primary loops and a plurality of series of intermediate or subsidiary loops of substantially the same length as the main or primary loops formed within the circuit of the main or primary loops.

2. A skein composed of a continuous length of thread formed into a series of main or primary loops and a plurality of series of intermediate or subsidiary loops, said intermediate or subsidiary loops being separable from the main or primary loops so as to form a skein consisting of a series of simple loops.

3. A skein composed of a continuous length of thread formed into a plurality of series of loops of comparatively short length, said loops being separable into a skein of comparatively long length and consisting of a series of simple loops.

4. A skein composed of a continuous length of thread formed into a plurality of series of loops unwindable by pulling on the thread or loop first wound and unfoldable into a skein of greater length than the original skein consisting of a series of simple loops.

5. A skein composed of a continuous length of thread, having a series of main or primary loops and a plurality of series of intermediate or subsidiary loops formed therein, all of said loops extending the entire length of the skein, the main or primary and the intermediate or subsidiary loops being in such relation with each other that upon pulling the thread first wound the skein is unwindable without entanglement.

6. A skein composed of a continuous length of thread formed into a series of main or primary loops and a plurality of series of intermediate or subsidiary loops of substantially the same length as the main or primary loops.

In testimony that I claim the foregoing as my invention, I have signed my name.

MAX OTTO CLAUSS.
